UNITED STATES PATENT OFFICE.

PATRICK J. MADDEN, OF CHICAGO, ILLINOIS.

PLUMBING-FIXTURE.

1,253,506.

Specification of Letters Patent. Patented Jan. 15, 1918.

Application filed June 6, 1918. Serial No. 772,132.

To all whom it may concern:

Be it known that I, PATRICK J. MADDEN, a citizen of the United States, residing at Chicago, in the county of Cook and State 5 of Illinois, have invented certain new and useful Improvements in Plumbing-Fixtures, of which the following is a specification.

While the present invention relates, and some of its features are applicable to plumbing fixtures generally, still it relates and all 10 of its features are applicable more particularly to water closets. Again, some of its features relate to plumbing fixtures of what are known in the art as "wall-hung" or 15 "stack-hung" type. It also relates to separate component parts of the fixture, as, for example, it relates in part to the construction of the bowl with a view to adapting it to perform the various functions required 20 of it; in part to the means for and the manner of supporting the bowl (and these features are adapted for use in any fixture having a bowl or other receptacle); and in part to the means for and the manner of forming 25 a tight joint between the bowl and its discharge pipe.

For the sake of brevity the term "wall hung" will be hereinafter used in many places and especially in the claims, but always with the understanding that wherever 30 it is used the term "stack hung" may be read for it, excepting, of course, in those instances in which "wall-hung" is specifically meant.

These several features are segregable, and I desire to have it understood that I reserve to myself the exclusive right to use all of them in one and the same fixture, or any of them apart from the others in any fixture, 40 or for any purpose, for which they may be adapted.

The objects of the several features will appear from the general description which follows, and the invention consists in the 45 features of novelty that are hereinafter described with reference to the accompanying drawings, which are made a part of this specification, and in which:

Figure 1 is a central sectional elevation 50 of a water closet embodying all of the several features of the invention, the plane of the section being indicated by the line 1-1, Fig. 2, and the parts being viewed in the direction of the arrow.

Fig. 2 is a plan view of said water closet. Fig. 3 is a view partly in side elevation

and partly in vertical section of the "bowl," including the "basin" and the parts that are accessory thereto and integral therewith, the plane of the section being approximately 60 indicated by the line 1, Fig. 2, and the line 3-3, Fig. 5.

Fig. 4 is a similar view with some of the parts broken away and others in section on a vertical plane at one side of the plane 65 of the section of Fig. 3.

Fig. 5 is a section on the line 5-5, Fig. 3, looking downward, in the direction of the arrow.

Fig. 5^a is a view similar to Fig. 5, but 70 showing a modification.

Fig. 6 is a front elevation of the means for transmitting movement from the hinged seat to the valve stem, adjacent portions of the seat being shown in vertical section on 75 the line 6-6, Fig. 2, and the parts being viewed in the direction of the arrows.

Fig. 7 is a sectional elevation thereof, on the line 7-7, Fig. 6, looking in the direction 80 of the arrows.

Fig. 8 is a perspective view of the packing-ring or gasket.

Considered in its entirety the body of the fixture, or what will hereinafter be called the "bowl", comprises a bowl proper 85 or basin-like portion, 1, (hereinafter called the "basin", for the sake of distinction), having a hollow rim, 2, of customary form, a hollow extension, 3, which is located at the back of the basin and extends upward 90 above the level of the hollow rim. A hollow trap-housing, 4, is located below the rear portion of the basin and a part 5, which will hereinafter be called the "horn".

The basin is shallow as compared with 95 the corresponding part of water closet bowls as customarily constructed, and its bottom slopes downward to an outlet opening, 6, the margin of which is rounded and merges imperceptibly with the inner surface of the 100 tubular portion, 7, of the horn, which tubular portion joins the under-side of the bottom of the basin around the opening, 6, and passes through a diaphragm, 8, the rear side of which directly joins the bottom of the basin, behind the horn, whence it slopes downward and forward, diverging from the bottom of the basin, its side and front edges being provided with an upwardly extending flange, or wall, 10, the 110 height of which is graduated to correspond with the angle of divergence of the dia-

phragm and the bottom of the basin. The portion, 9, of the horn which is below the tubular portion, 7, is of spherio-segmental shape, or like a segment of a hollow sphere, 5 and its open side is presented laterally with respect to the longitudinal axis of the tubular portion, 7, forming the ultimate discharge opening of the bowl, from which the discharged matter escapes before entering 10 the up-take leg of the siphonic discharge pipe. The diaphragm, 8, with its wall or flange, 10, and so much of the bottom of the basin as is bounded thereby, together form a water box 11, which surrounds the 15 tubular portion, 7, of the horn, as shown most clearly in Fig. 5, and, at two points, 12, on opposite sides of an axial plane passing through said horn, lengthwise of the bowl, joins the bottom portion of a water 20 passage, 13, which extends upward, back of the bowl, and at its upper end receives a superabundant quantity of water for supplying the jet opening, 14, which latter communicates directly with an extension, 11^a, 25 of the water box 11, which extension proceeds from the diaphragm, 8, downward along the front side of the horn. In fact, all of the water-ways or passages through which the water flows for supplying the jet 30 opening and the openings of the hollow rim, are of larger capacity than the opening itself, with the result that the water reaches the jet or other opening under practically full supply-pressure, the friction of the on-flowing water with the inner surface of the 35 walls of the water-ways or passages being practically eliminated. This materially increases the efficiency of the jet, not only in priming the siphon, but as a lifting agent 40 for driving before it the contents of the up-take leg of the siphon.

It should be noted that the projected longitudinal axis of the jet-opening, as indicated by dotted line π , in Fig. 1, is not concentric with the longitudinal axis of the up-take leg of the siphon, and hence the jet 45 of water issuing from said opening will not pass centrally through said up-take leg. The arrangement is such that the said projected 50 axis π passes a short distance above the dam, 15, of the siphon, so that the jet of water will just escape said dam and strike the far wall of the down-take leg, somewhat below the crown, 16. As shown in Fig. 1 of the 55 drawing, the parts are so constructed and located that the said projected axis π passes the same distance above the dam, as it passes below the submerged point, 17, of the trap. It may here be stated that the term trap is 60 here used as including such portions of the bowl and discharge pipe as are kept full of water, for the purpose of preventing gases from passing down through the up-take leg of the siphon, and reaching the discharge 65 opening of the basin. It is manifest that

the water will stand in the basin and other parts at the level of the over-flow level of the dam, 15, and this being so, it will be observed that the "trap" or water seal is formed partly in the up-take leg of the 70 siphon and partly in the bowl. It is found in actual practice that by giving the jet the described course, its efficiency is materially increased as compared with any other disposition of it, of which I am aware. It 75 forms a barrier across the upper portion of the down-take leg of the siphon and effectually prevents air from rising in said up-take leg to the crown of the siphon. Furthermore, whatever air may be in the 80 crown of the siphon is drawn out by the suction produced by the water flowing through the down-take leg. It does this so effectually that it has been demonstrated by actual practice that even if the clean-out cap 85 18, be removed, thereby opening the crown of the siphon to atmosphere, the siphon will nevertheless be primed, or having been primed, the siphonic action will not be broken, and this is more than has been accomplished by any heretofore existing arrangement of which I am aware. With all heretofore existing arrangements, the admission of air to the crown of the siphon 90 will either prevent the siphon from being primed in the first instance, or, if the priming has been accomplished, will break the siphonic action.

Aside from this coöperation of the jet in the siphonic action, the particular arrangement described gives it a lifting effect that will evacuate the basin, even to the extent of breaking the water seal in the trap, this being a result that will not follow if the jet is directed centrally through the up-take leg 10 of the discharge pipe. I advance no theory as to the superior efficiency due to the angular course of the jet, relatively to the axis of the discharge pipe, but may say that the statements above made have been proved by 11 actual practice.

For supplying the passage, 13, with water, its upper end communicates with a chamber, 19, in the extension, 3, of the bowl and the back wall of this chamber is formed by a 11 web, 20, having an opening which is occupied by the cylindrical portion, 21, of the easing of a valve device, 22. It is unnecessary, for the purposes of this application, to fully show or describe in detail the construction of this valve device. Suffice it to say that in all material respects it is like that shown in Patent #931,937, which was granted to me August 24th, 1909, its main portion being contained in a chamber, 23, 1 which is open at the back of the bowl, for receiving the water supply pipe connection, 24, the front of said chamber, 23, being formed by the web, 20. The valve device has a valve stem, 25, connected with the valve 1

proper, and arranged to operate as described in patent aforesaid, and this valve stem passes through an opening formed through the front wall of the chamber, 19. The 5 chamber, 19, is, in fact, a separate structure built within the hollow extension, 3, although a portion of the wall or shell of this latter forms the front wall of the chamber, 19, and is provided with an opening, 26, for 10 the passage and free end-wise movement of the valve stem, 25. The chamber, 19, also receives from the valve casing, 21, the water for supplying the hollow rim, 2, and to this end the bowl is provided with passages, 27, 15 which connect the hollow rim and the chamber, 19.

So much of the interior of the hollow extension, 3, as is not taken up by the chambers, 19 and 23, forms a chamber or passage, 28, 20 having branches, 29, which extend downward on opposite sides of the chamber, 19, and at their lower ends communicate with the interior of the bowl through openings, 30, located at the back thereof, and immediately below the hollow rim. The upper portion of the chamber or passage, 28, is open 25 at the back and communicates with a flue, 31, which is arranged to ultimately discharge into the atmosphere, the gases rising through 30 the branches, 29.

The entire bowl, including all of the parts bearing the reference numerals from 1 to 14 inclusive, and 20, with their described features are integral and may be of cast 25 metal, but following the present custom they are preferably molded of earthen-ware. As is well known to those skilled in the art, it is extremely difficult to make these articles of earthen-ware, especially where they have 40 a considerable number of more or less intricate internal passages, and have them practically perfect after they are baked, and this is a reason why it is also difficult to provide the earthen-ware parts with true bearing 45 surfaces, which must occupy practically exact relations to other parts to which the earthen-ware is connected, or with which it is associated. Great difficulty was experienced by the skilled potters who were employed to make the bowl shown in the drawings, which was, however, accomplished by the following steps which may be followed 50 in carrying out the invention, but which, on the other hand, may be departed from without departing from the spirit of the invention, as the steps and order of steps here set forth are not essential. The basin is 55 first molded of plastic clay and used as the basis of the structure, about which the other 60 parts are assembled. After it is formed, the opening, 6, is made through its bottom. The horn, 9, is separately formed, and, while still plastic, plastered against the under side 65 of the bottom of the basin, so that its cylindrical portion, 7, surrounds the opening, 6,

the joint being made perfect and the parts rounded off so as to avoid corners. The diaphragm, 8, with its wall or flange, 10, is then formed and pasted to the under side of the bottom of the basin, an opening being 70 formed through the diaphragm, so that it may be slipped over the horn, 9. The downwardly extending portion, 11^a, of the water box is then formed and pasted to the front side of the horn, 9, and to the under side of 75 the diaphragm, 8, an opening, 11^b, being formed through the diaphragm for placing the portions, 11 and 11^a, of the water box in communication with each other. The passage, 13, is formed separately and plastered 80 against the outside of the back of the basin, and the passages, 12, are formed in or between the united parts for connecting the lower portion of the passage, 13, with the rear portion of the water box, 11. The trap-housing, 4, is separately formed and plastered against the front and side edges of the diaphragm, 8, whence its sides extend upward and are pasted directly to the under 85 face of the rear side of the basin, terminating at the bottom face of the web, 22, which forms the bottom of the upper extension, 3. Above the level of this web the formation is 90 comparatively simple, and needs no particular description. The rear face of the bowl is 95 dressed off to a plane, so that it will fit flat against a wall, or a slab, 33, which is customarily used when a working space behind the fixtures is provided, as is the case with practically all of the so called "wall-hung" fixtures. Some of the features of the present 100 invention are particularly adapted for fixtures of this class, and one of my objects is to hang the fixture, not from the wall, although it has that appearance, but from the 105 soil stack, which is always of sufficient strength and stability to afford ample support for the entire fixture.

The fixture which is shown in the drawings for the purposes of illustrating the preferred embodiment of the invention, has a siphonic discharge pipe, the up-take leg, 34, of which communicates at its lower end with the discharge opening of the horn, 5, the tortuous down-take leg, 35, of which 110 communicates with the soil stack, 36, the connection between them being made by a screw joint, 37, or by any other means that will insure a tight joint and firmly support the siphonic discharge pipe, which latter is 115 of sufficient strength to sustain the entire weight of the fixture and any additional weight that may be put upon it.

The main center or point of support for the fixture as a whole is at the joint, of whatever construction it may be, between the lower end of the down-take leg, 35, of the siphonic discharge pipe and the soil stack, 36, and it is manifest that the tendency of the fixture to tilt forward and downward, under 120 125 130

the influence of its own weight and any load that is put upon it will produce great torsional strain upon this joint, tending to injure and weaken it. In order to eliminate this torsional strain as far as possible, and confine the strain upon the joint to a vertical strain parallel with the joint itself, and at right angles to the horizontal disposed lower end of the down-take leg of the siphonic discharge pipe, the latter is provided on its opposite sides with perforated lugs, 38, through which pass headed tie rods or bolts, 39, the heads of which bear against the front faces of the lugs, and the rear ends of which are screw threaded to receive nuts, 40, which bear upon the rear faces of lugs carried by a yoke, 41, which, in turn, bears against the rear side of the soil stack, the lugs of the yoke being perforated for the passage of the tie rods or bolts, 39, so that by tightening up the nuts on the tie rods or bolts, the latter may be put under tensile strain, and thereby prevent the siphonic discharge pipe from tipping forward.

The object in making the down-take leg of the siphon tortuous is to cause the water to be deflected across the water-way so as to form a sort of dam or cut-off for preventing the air from rising through the down-take leg to the crown of the siphon. I am aware that it is not broadly new to make the down-take leg of a siphon tortuous for a like purpose, but the use of a siphon of this construction in combination with a jet opening arranged to discharge a jet of water upward in the up-take leg, in the manner herein described, results in the complete and thorough evacuation of the basin even where the water supply is under low pressure, such as in fixtures having low-down flushing tanks.

In order to form a perfectly tight joint between the bowl and the up-take leg of the discharge pipe, the bowl is provided with a downwardly presented circular groove, 43, for receiving the upper side of a packing ring or gasket, 44, which is made of rubber or other elastic material, and is of rectangular or diamond-shape in cross section. The groove, 43, surrounds the horn, 9, and downwardly extending portion, 11^a, of the water box, and is so disposed that it forms equal angles with a vertical line passing through its deepest point. The lower or in-take end of the up-take leg, 34, of the siphon, is formed with a bell-mouth, 45, which is presented laterally with respect to the axis of the main portion of the leg, 34, and upwardly toward the basin. Its margin occupies a plane which is approximately parallel with said axis, forming an acute angle therewith, and said margin is provided with a V-shaped circular groove, 65, which is adapted to register with the groove,

43, throughout. The horn, 9, projects well into said bell-mouth and its lateral outlet opening is disposed opposite and with its axis practically coincident with the axis of said up-take leg, so that the discharge from the horn will be through said leg, longitudinally. Below the bell-mouth, 45, the bottom of the trap-housing, 4, is provided with a perforation, in which is placed a nut, 46, having an enlarged flange or shoulder, 47, which rests upon the upper surface of said bottom, and through this nut passes a correspondingly threaded screw, 48, the upper end of which is of conical or other suitable shape, and fits in a socket, 49, formed in a lug cast on the under side of the bell-mouth, 45, so that by tightening the screw it will exert pressure in opposite directions, upwardly and downwardly, upon the bell-mouth and the trap-housing, respectively. The entire weight of the "bowl" being supported by the siphonic discharge pipe, through the medium of the gasket, 44, it is manifest that this action of the screw will tend to force or draw the entire bowl downward, thus compressing the gasket and forming a water tight joint. Furthermore, this joint is entirely below the surface level of the water in the trap as already described, the advantage of which is well known by those skilled in the art. In order to still further insure against leakage at the joint thus formed, the packing ring or gasket is provided with an apron, 50, which joins the innermost angle of the gasket and hangs down in the space between the bell-mouth, 45, and the downwardly extending portion, 11^a, of the water box. This apron preferably extends through only a portion of the circumference of the packing ring or gasket.

The parts are so constructed, proportioned and arranged that the center of gravity of the bowl will pass about axially through the packing ring, so that the weight of the bowl itself will be about equally distributed throughout the packing ring with a tendency to tighten the joint between the bowl and the bell-mouth of the up-take leg of the discharge pipe, but without means for preventing it an added weight acting downwardly upon the front side of the bowl would tend to tip or tilt it forward and thereby open up or loosen this joint. For the purpose of preventing this the bowl is provided at its back with shoulders, 51, which are engaged by adjustable stops, 52, connected to perforated lugs or ears, 53, cast on the opposite sides of the siphonic discharge pipe. Screws (or bolts), 54, pass through perforations of the lugs, 53, and through correspondingly threaded openings formed through the stops, 52, so that by turning the screws in one direction the stops are drawn toward the lugs, 53, thereby drawing the

upper portion of the bowl backward, toward the soil stack, 36, and when turned in the opposite direction the stops are permitted to move farther away from the soil stack. This 5 permits the upper portion of the bowl to be moved outward in the manner and for the purpose presently to be described and the combined functions of the parts numbered 36 to 41 inclusive, coöperating with the 10 functions of the parts numbered 51 to 54, inclusive, tend to tighten the joint between the discharge pipe and stack and also the joint between the discharge pipe and bowl. The stops, 52, are of L-shape and at their feet 15 rest upon the upper flat sides of horizontal flanges, 55, which also are cast with and project from the opposite sides of the discharge pipe. The flanges, 55, are provided with slots, 56, indicated by dotted lines in 20 Fig. 1, into which project lugs, 57 (preferably of non-circular shape) extending downward from the under sides of the feet of the stops. By this means the stops are guided in their movements by the action of the 25 screws, 54, and prevented from moving around at random. While, as before stated, the entire weight of the bowl is sustained by the soil stack through the medium of the siphonic discharge pipe, the bowl will nevertheless, when overloaded at its front side, 30 have a tendency to tip forward moving about the front side of the joint formed by the packing ring, 44. When the fixture is installed and in readiness for use, this tendency to tip forward is prevented by the 35 stops, 52, and their accessories, but this capability of the bowl for being tipped forward is made use of in "hanging" and removing it. In order to remove it, assuming 40 the parts to be in the position in which they are shown in Fig. 1, excepting that the screws (or bolts) 54 have been turned to permit the stops, 52, to be moved forward, the bowl is lifted bodily upward, but lifted 45 a greater distance at the front side than at the back side, thus tilting it about the stops, which in this operation perform the functions of fulcrums. The upward movement 50 of the front side of the bowl should be sufficient to clear the packing ring, 44, and withdraw the horn, 9, from the bell-mouth of the discharge pipe, the construction and proportions of the parts being such that when the bowl is thus tilted upward about 55 the stops as a fulcrum, the horn will clear the bell-mouth of the discharge pipe, after which it may be moved outward and away, the entire back of the trap housing, 4, being open to permit the insertion and removal of 60 the up-take leg of the discharge pipe.

The reverse of these steps are followed in hanging the bowl. In order to prevent the accidental displacing of the packing ring, or gasket, it is provided on its under side with 65 a suitable number of teats, 58, in the nature

of dowel pins, which project into openings, formed to receive them, at the bottom of the circular channel in the margin of the bell-mouth. The construction just described enables the use of a trap-housing which is lower, 70 or of less vertical extent, than is required with the parts constructed and arranged as shown in my former Patent #897,914, granted Sept. 8th, 1908, and this is very desirable as it affords greater clearance between the bowl and the floor for giving access to the adjusting screws, 48, and for permitting the removal of dirt that may accumulate below the bowl. 75

To the seat, 60, is secured a plate, 61, 80 which crosses it from side to side, at the back, and joins at right angles a downwardly extending plate, 62, which faces its back edge. Arms, 63, formed with, or rigidly attached to the angle iron, formed by plates 85 61 and 62, project rearwardly from its ends, so as to lie upon the opposite sides of the hollow extension, 3, and the rear ends of these arms are perforated for the passage of a rod or pin, 64, which passes through openings in the sides of the extension, 3, and through the air chamber, 28 and carries at its ends retaining nuts, 65. This forms a hinged joint about which the seat may be raised and lowered. To the under side of 95 the seat is secured a curved plate, 66, which follows the contour of the seat, and formed with this plate are internally screw threaded sockets, 67, which are engaged by screws, 68, which pass through the plate, 61, their heads 100 being counter-sunk, as shown more clearly in Fig. 6. Formed with the plate, 66, are upwardly extending standards, 69, which are perforated near their upper ends for passage of a pivot pin, 70, which passes through 105 a perforation formed at the angle of a bell crank lever, having a downwardly extending arm, 71, which engages an anti-friction roller, 72, journaled to the forward end of the valve stem, 25, the plate, 62, being provided with an opening, 73, in order to permit the arm, 71, to contact with the roller, 72. The other arm, 74, of this bell crank lever is horizontal, lying beneath the plate 110 61, and is jointed at 75, to perforated ears 115 on a nut, 76, which is engaged by a screw, 77, swiveled to the plate, 66, so that by turning the screw in one direction or the other, the position of the arm, 71, relatively to the valve stem, may be adjusted in the manner 120 and for the purpose shown and described in my former Patent, #569,559, dated Oct. 13th, 1896.

It will be understood that the rear side of the seat is cut away or recessed, in order to 125 accommodate all of the parts just described for transmitting movement from the seat to the valve stem.

Fig. 5^a shows a modification of the construction shown in Fig. 5, the only differ- 130

ence being that in Fig. 5 the water passage for supplying the water box is divided and communicates with the water box at its opposite sides, while in Fig. 5^a that portion of 5 the water box which is above the plane of the packing ring does not extend completely around the outlet opening of the basin, but only far enough to conduct the water from the passage, 13, to the opening, 11^b, between the portions 11 and 11^a of the water box.

10 It is preferable to divide the water-way for supplying water to the jet opening into two passages which extend around the outer sides of the horn of the basin as shown in Fig. 5, because it produces a more even distribution of the water and tends to avoid the objectionable whistling or hissing sound that is usually produced by the jets of water in fixtures of this type.

20 What I claim as new and desire to secure by Letters Patent is:

1. A plumbing fixture having a bowl comprising a basin provided through its bottom with an outlet opening, a hollow horn joining the basin around said opening and projecting downward therefrom, a discharge pipe terminating at its intake end in a bell mouth presented laterally relatively to the axis of said pipe and upwardly toward the 25 basin, into which bell-mouth the hollow horn projects, said horn having a lateral discharge opening presented in the direction of the axis of the intake leg of the discharge pipe, the basin being seated upon and supported by said bell-mouth, and means for supporting said discharge pipe with its bell-mouth clear of the floor.

2. A stack-hung plumbing fixture having a bowl comprising a basin provided through 40 its bottom with an outlet opening, a hollow horn joining the basin around said opening and projecting downward therefrom, a discharge pipe having an in-take leg terminating at its in-take end in a bell-mouth presented laterally relatively to the axis of said intake leg and upwardly toward the basin into which bell-mouth the hollow horn projects, said horn having a lateral discharge opening presented in the direction of the 45 axis of the intake leg of the discharge pipe, into which bell-mouth the horn projects, the basin being seated upon and supported by said bell-mouth, and means for connecting the discharge pipe to a stack, whereby it is supported independently of the floor.

55 3. A wall-hung or stack hung plumbing fixture having a bowl comprising a basin provided through its bottom with an outlet opening, a hollow horn joining the basin 60 around said opening and projecting downward therefrom, a discharge pipe having an upwardly inclined intake leg terminating at its intake end in a bell-mouth presented laterally relatively to the axis of said intake leg and upwardly toward the basin into

which bell-mouth the hollow horn projects, said horn having a lateral discharge opening located opposite and presented in the direction of the upwardly inclined in-take leg of the discharge pipe in position to discharge directly into and through said upwardly inclined in-take leg, longitudinally, the basin being seated upon and supported by said bell-mouth and means for supporting the discharge pipe independently of the 75 floor.

4. A wall-hung or stack hung plumbing fixture having a bowl comprising a basin provided through its bottom with an outlet opening, a hollow horn joining the basin around said opening and projecting downward therefrom, a discharge pipe having an upwardly inclined intake leg terminating at its intake end in a bell-mouth presented laterally relatively to the axis of said upwardly inclined intake leg and upwardly toward the basin, into which bell-mouth the hollow horn projects, said horn having a lateral discharge opening presented in the direction of the axis of the upwardly inclined in-take leg of the discharge pipe in position to discharge directly into and through said intake leg, longitudinally, the basin being seated upon and supported by said bell-mouth and means for supporting the discharge pipe 95 independently of the floor, said horn having also a jet opening arranged to discharge a jet of water into and longitudinally through said upwardly inclined intake leg.

5. A plumbing fixture having a bowl comprising a basin provided through its bottom with an outlet opening, a hollow horn joining the basin around said opening and projecting downward therefrom, a siphonic discharge pipe having an upwardly inclined in-take leg, the lower in-take end of which terminates in a bell-mouth presented laterally relative to the axis of said pipe and upwardly toward the basin, into which bell-mouth the hollow horn projects and upon which the basin is seated so as to be supported thereby, said horn having a lateral discharge opening located opposite the inclined intake leg of the discharge pipe and presented in a direction to discharge directly into and through said in-take leg, longitudinally, said horn having also a jet opening disposed with its projected axis at an angle to the longitudinal axis of the intake leg of the siphon and passing in close proximity to the 110 dam or overflow level of the siphon and means for supporting said discharge pipe with its bell-mouth clear of the floor.

6. A stack-hung plumbing fixture having a bowl comprising a basin provided through 125 its bottom with an outlet opening, a hollow horn joining the basin around said opening and projecting downward therefrom, a siphonic discharge pipe having an inclined up-take leg, the lower end of which terminates

nates in a laterally presented bell-mouth into which the hollow horn projects, said hollow horn having a jet opening located with its extended axis at an angle to the axis 5 of said up-take leg, a soil stack with which the lower end of the down-take leg of the siphon communicates, the discharge pipe and soil stack being located with their axes in a common plane, a connection between the soil 10 stack and the siphonic discharge pipe at a point above the lower end of the down-take leg of the latter for bracing the siphonic discharge pipe and preventing it from tilting or tipping away from the soil stack, a shoulder having a forwardly presented bearing 15 surface on the upper portion of the bowl, a stop engaging said shoulder, and adjustable means engaging said stop and connected to the upper portion of the siphonic discharge 20 pipe for preventing the bowl from tipping forward.

7. A plumbing fixture having a bowl comprising a basin provided through its bottom with an outlet opening, a hollow horn of 25 spherio-segmental shape joining the basin around said opening and projecting downward therefrom, a siphonic discharge pipe having an upwardly inclined in-take leg, the lower in-take end of which terminates in a bell-mouth presented laterally relative to the axis of said pipe and upwardly toward the basin, into which bell-mouth said hollow horn projects, and upon which the basin is seated so as to be supported thereby, said 30 horn having a lateral discharge opening located opposite the inclined in-take leg of the discharge pipe and presented in the direction of the longitudinal axis of said in-take leg, said horn having also a jet opening so disposed that its projected longitudinal axis forms an angle with the axis of the inclined in-take leg and passes in proximity to the 35 dam or overflow level of the siphonic discharge pipe, and means for supporting said discharge pipe with its bell-mouth clear of the floor.

8. A plumbing fixture having a bowl comprising a basin provided through its bottom with an outlet opening, a hollow horn joining the basin around said opening and projecting downward therefrom, a discharge pipe having an inclined in-take leg, the lower end of which terminates in a bell-mouth presented laterally relative to the axis of 40 said intake leg and upwardly toward the basin into which bell-mouth the hollow horn projects, said horn having a lateral discharge opening presented upwardly and rearwardly in the direction of the longitudinal axis of said up-take leg and an elastic packing ring surrounding the horn and through which the horn projects, whereby said packing ring contacts with the basin around the horn and with the margin of the 45 bell-mouth of the up-take leg of the dis-

charge pipe, and means for forcing the bowl and the bell-mouth of the discharge pipe toward each other for compressing the gasket and forming a water tight joint between them. 76

9. A plumbing fixture having a bowl comprising a basin provided through its bottom with an outlet opening, a hollow horn joining the basin around said opening and projecting downward therefrom, a discharge pipe having an inclined up-take leg, the lower end of which terminates in a bell-mouth presented laterally relative to the axis of said pipe and upwardly toward the basin, into which bell-mouth the hollow horn projects, said horn having a lateral discharge opening presented upwardly and rearwardly in the direction of the longitudinal axis of said up-take leg and an elastic packing ring surrounding the horn and through which the horn projects, whereby said packing ring contacts with the basin around the horn and with the margin of the bell-mouth of the up-take leg of the discharge pipe, and means for forcing the bowl and the bell-mouth of the discharge pipe toward each other for compressing the gasket and forming a water tight joint between them, the dam or overflow level of the discharge pipe being above the level of the packing ring, whereby the joint formed by said packing ring is water sealed. 80

10. A stack hung plumbing fixture having a bowl comprising a basin provided through its bottom with an outlet opening, a hollow horn joining the basin around said opening and projecting downward therefrom, a siphonic discharge pipe having an inclined up-take leg terminating at its lower end in a bell-mouth into which said horn projects, said horn having a lateral discharge opening presented in the longitudinal direction of the axis of said up-take leg and having also a jet opening so disposed that its projected axis forms an angle with said up-take leg and passes above the dam or overflow level of the said siphonic discharge pipe, a soil stack with which the down-take leg of said siphonic discharge pipe communicates laterally, means for forming a water tight joint between said down-take leg and said pipe, a packing ring contacting with said bell-mouth and with the bottom of the basin and through which said horn projects, means for connecting the upper portion of the siphonic discharge pipe with the soil stack and means for connecting the upper portion of the bowl with the upper portion of the siphonic discharge pipe, whereby the weight of the fixture tends to tighten the joints between the discharge pipe and soil stack and between the discharge pipe and bowl. 110

11. A plumbing fixture, having a bowl, comprising a basin, provided through its bottom with an outlet opening, a hollow horn 115

joining the basin around said opening and projecting downward therefrom, a water-box, one wall of which is formed by the front wall of said horn, a jet opening through which the water-box and the interior of the horn communicate, a water-way or passage, one wall of which is formed by the rear wall of the basin, communicating with the water-box, in combination with means for supplying water to the water-way, and a discharge pipe, the intake end of which is in communication with the outlet of the basin and is located opposite the jet opening.

12. A plumbing fixture, having a bowl, comprising a basin, provided through its bottom with an out-let opening, a hollow horn joining the basin around said opening and projecting downward therefrom, a water box, one wall of which is formed by the front wall of said horn, a jet opening through which the water box and the interior of the horn communicate, a water-way or passage, one wall of which is formed by the rear wall of the basin, and separate water-ways or passages extending around the outer sides of the horn and communicating with the water-way aforesaid, and communicating also with the water box on opposite sides, respectively, of the central plane of the horn, in combination with means for supplying water to the water-way first aforesaid, and a discharge pipe, the in-take end of which is in communication with the out-let of the basin, and is located opposite the jet opening.

13. A bowl for plumbing fixtures, comprising a basin having a hollow rim and having through its bottom an outlet opening, a discharge pipe communicating with the outlet opening, a hollow horn joining the basin around said opening and projecting downward therefrom, said horn having a laterally presented discharge opening, a water box, one wall of which is formed by the horn, a jet opening arranged to discharge a jet of water outward through the

discharge opening of the horn and into the discharge pipe, a water-way or passage for supplying the jet opening, said water-way or passage being arranged at the back of the bowl and having separate branches extending around the opposite sides of the horn and communicating with the water box, said bowl having an extension located at the back of the basin and extending above the top thereof, said extension having a water chamber communicating with the aforesaid water-way and also with the hollow rim, and said extension having also an air chamber having an outlet opening adapted to communicate with an air flue and air ducts or passages extending from the air chamber downward upon opposite sides of the water chamber and opening into the basin below the hollow rim.

14. A plumbing fixture having, in combination, a bowl, comprising a basin, provided with a discharge opening, a siphonic trap arranged with its up-take leg in inclined position, the lower in-take end of said leg having a laterally presented mouth, terminating in a plane approximately parallel with the longitudinal axis of said up-take leg and communicating with said discharge opening, a packing ring, an upwardly presented seat for said packing ring formed on the discharge pipe around its mouth, a downwardly presented bearing surface for said packing ring, formed on the bowl around its discharge opening, a soil stack, means for rigidly connecting the discharge end of the siphonic trap with the soil stack, whereby the trap is supported by the stack with its in-take leg in upwardly inclined position, and means engaging the bowl at a level above the in-take end of the discharge pipe for drawing the upper portion of the bowl backward, toward the soil stack.
